CARL J. LINDEGREN, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

MULTICOLOR WEFT-REPLENISHING MECHANISM

Application filed January 5, 1929. Serial No. 330,633.

This invention relates to weft replenishing mechanisms more particularly of the multi-color type and it is the general object of the invention to provide a mechanism of this type with improved compartments for the bobbins.

The usual form of multicolor weft replenishing magazine comprises a plurality of vertical stacks of bobbins, bobbins of each stack being distinctive from the bobbins of the other stacks. The stacks are held by guideways for the tips and butts of the bobbins and in the case of a four-color magazine, for instance, there are two pairs of guideways for the butts of the bobbins. Each pair is formed in part by a thin web extending vertically along the inside plate of the magazine. The outer walls of the compartments of each pair are formed of other webs also cast integral with the inside plate. I find that as a matter of practical construction it is desirable to omit the dividing webs or partitions which have heretofore been cast integral with the frame and in their place substitute a separate element which may be secured in any approved manner to the inside plate of the magazine. Such a construction considerably simplifies the molding of the plate and permits a certain amount of freedom in the application of the weft to the magazine so as to define compartments of varying widths.

It is becoming increasingly common to mix artificial silk such as rayon with cotton or worsted yarns so that there are cross stripes of rayon or similar synthetic yarn separated by picks of other yarn. It is customary to wind silk, either the natural or the artificial product, on bobbins which are somewhat smaller than is usual either with cotton or worsted, so that a magazine is called upon to handle bobbins which vary in size not only with respect to length but also butt diameter, the diameter of the butts of the silk or rayon bobbin usually being less than that for cotton or worsted. It is a further object of my

present invention to provide a removable partition to define a pair of bobbin guideways so disposed that the guideways will be of different widths to accommodate bobbins of different butt diameters.

I have found by experiment that wood is an acceptable substitute for the usual cast iron head, but I do not wish to be limited to this material, inasmuch as my invention relates more directly to the size of the partitions and also the fact that they are removable.

Where the guideways for the butts of the bobbins are substantially larger than the diameter of the bobbin it is found that rolling of the bobbin results with consequent tightening of certain yarns and unwinding of others. By the use of removable partitions the widths of the compartments may be adapted particularly to the sizes of bobbin butts being employed. It is to be understood that although the bobbins may vary in size both as to length and butt diameter yet the shuttles will ordinarily be of the same size to facilitate boxing, the shuttles adapted for use with the smaller bobbins having spring clips proportioned to take the heads or butts of the small bobbins.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a top plan view of a weft replenishing mechanism made according to my present invention,

Fig. 2 is a vertical section on line 2—2 of Fig. 1,

Fig. 3 is a horizontal detailed section on line 3—3 of Fig. 2, and

Fig. 4 is a view similar to Fig. 3 but showing a different arrangement of removable partitions.

Referring to Figs. 1, 2 and 3, I have shown an inside magazine plate 10 which may be supported in any approved manner by means not shown. From said plate extend tie rods 5 11 on the outer ends of which are supported an outer plate 12, the latter plate being provided with vertical guideways 13 for the tips 14 of the bobbins B, said guideways directing the tips of the bobbins downwardly toward transfer position.

The plate 10, as shown more particularly in Figs. 1 and 2, is provided with side flanges 15 and 16, respectively, and a central flange 17. In the form of the invention set forth 15 herein the bobbins are arranged in pairs between the central flange and one or another of the outside flanges 15 or 16.

The matter thus far described is of common construction and forms no part of my 20 present invention, being substantially the same as that shown in prior Patent No. 1,030, 748, to which reference may be had for a more complete disclosure of the magazine and its operation.

25 In order to define proper spaces for the movement of individual stacks of bobbins I insert between the central flanges 17 and the outside flanges removable strips or partitions which define with the flanges the necessary 30 bobbin compartments. As shown in Figs. 1 and 2 there is located between the rear flange 16 and the central flange 17 a removable partition 20 which is held in position by means of screws 21, said partition being preferably so 35 formed that it defines with flanges 16 and 17 bobbin guides of equal width.

There is located between the front flange 15 and the central flange 17 a second partition 30 held in position by screws 31. Said 40 partition is so formed, however, as to define a relatively narrow bobbin butt guide 32 and a second guideway 33 which is substantially of the same width as those defined by partition 20 with flanges 16 and 17. The screws 45 preferably pass through openings 34 which are centrally disposed with respect to the central flanges and the outside flanges so that when the removable partition of the form 20 is employed two compartments or guideways of equal widths will be defined.

As shown in Figs. 1, 2 and 3 the partition 30 acts to define a compartment for a single stack of relatively small bobbins S which may have wound thereon silk, rayon or any form 55 of yarn which is customarily wound on a small bobbin.

As shown in Fig. 4 I have provided a third form of partition 40 which may form two relatively narrow compartments 41 and 42. It is to be understood that in the weaving of mixed fabrics there may be a decorative stripe of only one color in which case the form of magazine shown in Figs. 2 and 3 will be employed, or there may be decorative stripes of

two colors in which case the form of magazine shown in Fig. 4 will be employed.

It will be readily seen that the magazine may be adapted to the use of one or two distinctive decorative yarns, according to which is desired, without changing the major castings of the magazine as formed. By combining the strip 30 with the strip 40, for instance, it will be possible to make a magazine having three decorative stripes of fine yarn of different characteristics, there being one body filling to be made of the larger cotton or worsted yarn.

From the foregoing it will be seen that I have provided a very simple means for enabling the user of a magazine made according to my present invention to employ bobbins having smaller butt diameters than is usual when weaving cotton or worsted and that by a proper choice of the partitions any desired number of different decorative yarns up to the capacity of the magazine may be employed. It will also be seen with respect particularly to partition 30 that the same may be reversed so that the narrow compartment 32 will be to the right of the partition instead of to the left as viewed in Fig. 2. This may at times be a matter of practical advantage where the shifting of the shuttle boxes not shown might render it desirable to have an infrequently called decorative yarn located in a particular part of the magazine. It will also be seen that the separate partitions, which may be made of any desired material, facilitate the casting for the inside plate 10. While there is some variation also in the diameter of the tips of the bobbins yet this variation is not objectionable, but if desired the principle set forth herein may be extended to the outside plate of the magazine.

Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism having a frame with a pair of relatively spaced bobbin guiding elements, a partition separate from the elements, means cooperating with the frame and located substantially midway between said elements to hold the partition to the frame, said partition defining with the elements a pair of bobbin guides, said partition being wider on one side of the securing means than on the other side thereof to define bobbin guideways of different widths, said partition being reversible so that the narrower compartment may be on either the right or left hand side of said partition.

2. A set of partitions for a weft replenishing mechanism having fixed bobbin guiding

flanges between which are located centrally with respect to said flanges securing means to cooperate with the partitions, said set including a partition which is symmetrical with respect to the securing means to define with the flanges bobbin guides of equal widths, and said set including also a partition the points of attachment for the securing means of which are non-symmetrical with respect to the vertical sides of the partition, said second partition forming with the flanges two compartments of unequal widths.

10 In testimony whereof I have hereunto affixed my signature.

15 CARL J. LINDEGREN.
